UNITED STATES PATENT OFFICE.

ALEXANDER T. BELL, OF CHICAGO, ILLINOIS.

DUPLICATING-MACHINE.

1,224,702.

Specification of Letters Patent.

Patented May 1, 1917.

Application filed August 9, 1916. Serial No. 113,960.

To all whom it may concern:

Be it known that I, ALEXANDER T. BELL, a citizen of the United States, residing at Chicago, in the county of Cook and State 5 of Illinois, have invented certain new and useful Improvements in Duplicating-Machines, of which the following is a specification.

The present invention relates to a machine 10 in which are placed duplicating sheets having applied to a surface thereof, a layer of chemically prepared material, which will receive and retain within itself, and within limited areas, ink or coloring matter from 15 writing or other matter, whereby a plurality of copies of the written or other matter may be obtained by pressing sheets of paper on to said prepared surface to which said ink or coloring matter has been applied.

One object of the invention is to provide 20 means for holding a series of these duplicating sheets at one end of the machine, and to arrange the holding means for such sheets 25 so that the sheets can be passed from one position to another, allowing the placing and removing of the various sheets from the surface of the table, thereby rendering said sheets interchangeable and of a loose-leaf 30 variety.

A further object of the invention is to provide a shiftable mounting for the duplicating sheet holding means, to enable the 35 movements of the sheets in the manner above specified.

A further object of the invention is to provide means for enabling fresh duplicating sheets to be inserted upon the holder, but to render the holder of closed 40 formation, so as to eliminate the accidental disengagement of the sheets therefrom.

A further object of the invention is to arrange means along the edges of each sheet 45 for holding it in place, whereby no strain will be placed upon the sheet itself during the holding operation.

The invention further consists in the features of construction and combination of parts hereinafter described and claimed.

50 In the drawings:

Figure 1 is a vertical section of the machine of the present invention, showing one duplicating sheet placed above the table but out of use, a second sheet placed on the 55 table and ready for use, and a third sheet placed below the table and out of use;

Fig. 2, a plan view of said machine;

Fig. 3, a detail section of the forward end of the machine, showing the holder for the duplicating sheets raised in the manner 60 necessary when moving a sheet from a point above the table to a point below;

Fig. 4, a detail of the mounting for the gage member;

Fig. 5, a detail of one end of the plate 65 which closes the open side of the duplicating sheet holding frame;

Fig. 6, a detail of one end of the duplicating sheet;

Fig. 7, a cross section through one end of 70 one of said sheets; and

Fig. 8, a detail showing the configuration 75 of the wire inserted along the edge of the duplicating sheet, with the metal clip and duplicating sheet in place thereon.

In the art to which the present invention relates, there are known certain chemically prepared substances any of which when placed on sheets or plates constitute a hectographic sheet or plate. These substances 80 are capable of absorbing and retaining within themselves ink or coloring material within specified areas, and by taking matter having ink or coloring material thereon and pressing it upon the surface of such substance, a portion of the ink or coloring matter will be absorbed or retained in the body of such substance. Then by taking a blank piece of paper and pressing it upon the surface of the substance, a portion of the ink 90 or coloring matter retained therein will be transferred to the blank piece of paper, and thus a reproduction of the original writing or other matter will be obtained. The amount of ink absorbed by such substances 95 will be sufficient to enable a plurality of such reproductions to be obtained.

In the present invention, a machine is disclosed for use with such form of duplicating sheet, and it is intended to mount the 100 sheets after the manner of loose leaves, whereby any particular sheet can be brought into use from time to time as desired, or placed in position out of use, thereby enabling the user to make up a number of 105 these duplicating sheets, each with a different writing thereon, and then by a simple and quick manipulation place upon the table of the machine, in position for use, any selected one of the duplicating sheets which 110 has upon it the writing it is desired to duplicate.

Referring now to the drawings, the machine comprises a base 9, upon which is mounted a table 10. Both the base and table may be of any suitable style and size. Extending from the table, at what will be termed the forward end of the machine, are companion rails 11. Extending between these rails is a rod or bar 12; and lugs or projections 13 extend from each of the rails 11 to limit the downward movement of this bar 12 with respect to said rails.

Connected to each end of the bar 12 is an arm 14, each of which arms is connected to an arm 15 by a suitable pivot pin 16; and the arms 15 are each joined by means of a stud or pivot 17 to a rail 11. This forms a folding pivotal connection between the bar 12 and rails 11, allowing this bar to be swung upward from the rails, the function 20 of which will hereinafter appear.

Connected to the bar 12 are duplicating sheet receiving frames 18 and 19. Both are alike in configuration and arrangement, and a detailed description of only one will be entered into. Said holders each consist of a front rail 20, a top rail 21, a rear rail 22, and a bottom rail 23; and the front rail 20 has a bent portion 24, which is entered into the bar 12. The bottom rail 23 is spaced 30 away from said bar to provide an opening 23^a, and to close this opening a plate 26 is employed held normally in closed position by a spring 26^a (see Fig. 5), carried by the bar 12. This plate extends clear across from 35 the holder 18 to the holder 19, as will be apparent from Fig. 2.

The duplicating sheets 27 are double-backed, or otherwise reinforced, at the ends 28; and in this reinforced portion, at each 40 end, is inserted a wire 29, which is cut away at intervals to produce a reduced portion 30 (see Fig. 8). About this reduced portion are placed metal tabs 31, each having an opening 32 therein. The tabs at the 45 front end of the sheet will be inserted upon the wires of the frames 18 and 19, while the tabs at the rear end of the sheet will be passed over lugs or pins 33 on the top surface of the table 10.

In use, the spring-pressed plate 26 is 50 swung out of the way, and a plurality of duplicating sheets are inserted upon the wire holders 18 and 19 and placed upon the front bars 20 of said holders, as indicated by the numeral 34 in Fig. 2. When it is desired to use one of these sheets, it is moved upward on the bar 20 across the bar 21 and dropped down upon the bar 22 until it rests on the surface of the table, as indicated by 55 the numeral 35 in Fig. 1. The tabs at the rear end of the sheet when so placed upon the table are passed over the studs or pins 33. A gage member 36 is then placed in position, which gage member is carried by, and 60 adjustable upon, a rod 37, held in clips 38.

On one end of the rod is a thumb-nut 39 for affixing the clips securely to the table and holding the rod carrying the gage in fixed position. By loosening the thumb-nut, the clips can be disengaged from the sides of 70 the table to allow the gage to be shifted lengthwise of the duplicating sheet, or removed entirely from the table. By adjusting the gage along the rod 37, it may be moved sidewise of the duplicating sheet to 75 a desired point. The gage is adjusted to bring the paper when placed upon the duplicating sheet in proper position to such area of the body of the substance as may have the ink contained therein.

After sufficient duplications have been made, the rod 12 is elevated as shown in Fig. 3, which is possible by reason of its jointed hinged connection to the rails 11, and the duplicating sheet, which has been previously 80 used, is positioned upon the lower bar 23, as indicated by the numeral 40 in Fig. 1. This means of handling the sheets can be carried on to the extent desired, and when necessary to again use a sheet that has been 85 previously used, the bar 12 and sheet holders can again be elevated as in Fig. 3, and the sheets brought from the lower rail 23 of the sheet holding frames up into position to be placed upon the surface of the table. 90 This gives a mounting for the sheets, so that they are arranged in loose-leaf order and can be interchanged as desired; that is, passed from a position above the table to a 95 position below, or from below to above.

The invention is of course susceptible to modification and is not deemed to be limited in any other manner than may be by the terms of the appended claims.

I claim:

1. In a duplicating machine, the combination of a table, a holder adjacent one end of the table adapted to slidably carry duplicating sheets, and means permitting a shifting of said holder away from the table to allow a sheet to slide upon the holder and to pass from a position above the table to a position below the table, substantially as described.

2. In a duplicating machine, the combination of a table, a holder adjacent one end of the table adapted to slidably carry duplicating sheets, a swinging support for said holder to permit a movement of said holder away from the table and allow selected ones of said sheets to slide upon the holder and pass from a position above the table to a position below the table, substantially as described.

3. In a duplicating machine, the combination of a table, a holder adjacent one end of the table adapted to slidably carry duplicating sheets, a foldable and swinging support for said holder to permit a movement of said holder away from the table and allow se- 125 130

lected ones of said sheets to slide upon the holder and pass from a position above the table to a position below the table, substantially as described.

5 4. In a duplicating machine, the combination of a table, a holder adjacent one end of the table, consisting of companion frames adapted to slidably carry duplicating sheets, and means permitting a shifting of said holder away from the table to allow selected ones of said sheets to slide upon said frames and pass from a position above the table to a position below the table, substantially as described.

15 5. In a duplicating machine, the combination of a table, a bar at one end of the table, a shiftable support for said bar, companion oppositely-disposed duplicating sheet holders carried by said bar adapted to slidably carry duplicating sheets, and said bar when shifted placing the holders in position to permit a sheet to slide upon said holders and move into a position on or off the table, substantially as described.

25 6. In a duplicating machine, the combination of a frame, a table carried by the frame, a bar at one end of the table, companion oppositely-disposed duplicating sheet holders on the bar adapted to slidably carry 30 duplicating sheets, pivoted arms connected to and carrying the bar, members attached to said frame and to which said arms are pivotally connected, and said bar when swung about the pivot of said arms placing 35 said holders in position to permit a sheet to slide from one position upon said holders to another and place said sheet in a position on or off the table, substantially as described.

7. In a duplicating machine, the combination of a table, companion oppositely-disposed frame-like holders for duplicating sheets arranged at one end of the table and adapted to slidably carry said sheets, one side of each holder being open, a closure for 45 said open sides of said holders, a shiftable mounting for said holders to permit their

assuming a position which allows a duplicating sheet to slide thereon and be placed in positions on and off the table, substantially as described.

50 8. In a duplicating machine, the combination of a table, a series of duplicating sheets, a holder for said sheets at one end of the table adapted to slidably carry the said sheets, and a mounting for said holder enabling a movement thereof to permit a duplicating sheet to slide upon said holder and be moved to positions on and off the table, substantially as described.

55 9. In a duplicating machine, the combination of a table, a holder for duplicating sheets adjacent one end of the table, said holder comprising a rectangular frame arranged when in normal position partially above and partially below the table, and 60 means for shifting said holder to allow a duplicating sheet to move from that part of the holder above the table to that part of the holder below the table, substantially as described.

65 10. In a duplicating machine, the combination of a table, a holder for duplicating sheets adjacent one end of the table, a tab extending from the end of the duplicating sheet and adapted to engage with the holder, 70 a supporting member in said end of said sheet to which said tab is secured, and said sheet being cut away at the point of engagement between said tab and supporting member, substantially as described.

75 11. In a duplicating machine, the combination of a table, a holder for duplicating sheets adjacent one end of the table, a tab secured to one end of said sheet and adapted to engage with the holder, a wire inserted 80 in said end of said sheet, said wire being grooved to receive said tab, and said sheet being cut away at the point of engagement between said tab and wire, substantially as described.
